(57) **CLAIM**

The ornamental design for a “dispensing closure,” as shown and described.

DESCRIPTION

FIG. 1 is a perspective view showing our new design;

FIG. 2 is a first side elevational view;

FIG. 3 is a second side elevational view;

FIG. 4 is a top plan view;

FIG. 5 is a perspective view showing our new design without probable environmental structure;

FIG. 6 is a first side elevational view without probable environmental structure;

FIG. 7 is a second side elevational view without probable environmental structure; and,

FIG. 8 is a top plan view without probable environmental structure.

Any broken lines in the drawings depict probable environment only and form no part of the claimed design.
